UNITED STATES PATENT OFFICE

KNUD KNUDSEN, OF DANBURY, CONNECTICUT, ASSIGNOR TO THE DANBURY ELECTRIC MANUFACTURING COMPANY, A CORPORATION OF CONNECTICUT

DESIGN FOR A SMOKER'S APPLIANCE

Application filed January 24, 1930. Serial No. 34,276. Term of patent 7 years.

To all whom it may concern:

Be it known that I, KNUD KNUDSEN, a citizen of the United States, residing in Danbury, county of Fairfield, State of Connecticut, have invented a new, original, and ornamental Design for Smokers' Appliances, of which the following is a specification, reference being had to the accompanying drawing, forming part thereof.

The accompanying drawing shows in Figure 1 a plan view and in Figure 2 a side elevation of my new design.

I claim:

The ornamental design for a smoker's appliance substantially as shown.

KNUD KNUDSEN.
